(No Model.)

J. J. BROPHY.

FIRE ALARM BOX APPARATUS.

No. 259,086.

Patented June 6, 1882.

UNITED STATES PATENT OFFICE.

JAMES J. BROPHY, OF NEW YORK, N. Y.

FIRE-ALARM-BOX APPARATUS.

SPECIFICATION forming part of Letters Patent No. 259,096, dated June 6, 1882.

Application filed April 24, 1882. (No model.)

To all whom it may concern:

Be it known that I, JAMES J. BROPHY, of the city, county, and State of New York, have invented a new and Improved Detective-Alarm 5 for Fire-Alarm Boxes, of which the following is a full, clear, and exact description.

Fire-alarm boxes as usually arranged are accessible for sounding an alarm by a door which is opened by a key, so that any one in possession of a suitable key may give the alarm. It has been found necessary in connection with these boxes to prevent the giving of false alarms, and to do this various methods have been proposed. In some cases the hinged doors of the 15 boxes have been constructed to give a local alarm when opened; but this is objectionable for several reasons, especially because the local-alarm bell being accessible through apertures made in the box for escape of the sound, 20 and completely accessible when the door is opened, its operation can be stopped, and, further, as the doors of such boxes are opened at frequent intervals by inspectors, the alarm has been an annoyance. In addition, the alarm 25 is insufficient on account of the small size of gong that can be received in the box. It has also been proposed to give the local alarm by placing the key at some point adjacent to the fire-alarm box in connection with the alarm, 30 which is sounded on removal of the key; but that is useless in the light of experience, which shows that the regular keys are seldom, if ever, used by persons giving false alarms. There 35 are other practical objections to any of the methods heretofore proposed for detecting false alarms.

My invention consists in a mechanism for giving a local alarm, which is brought into operation by mechanical devices only when 40 the pull by which the fire-alarm is given is moved, so that the usual construction and arrangement of the boxes are not changed in any respect, and the door is left free to be opened and closed, as usual.

45 I further provide for obviating all the difficulties connected with the arrangement of such a local alarm and prevent any tampering with it, as hereinafter described and claimed.

Reference is to be had to the accompanying 50 drawings, forming a part of this specification, in which similar letters of reference indicate corresponding parts in all the figures.

Figure 1 is an elevation, showing a fire-alarm box as applied upon a telegraph-pole

and provided with my alarm devices. Fig. 2 55 is an elevation of a fire-alarm box with both the inner and outer doors open to show the circuit-closing mechanism. Fig. 3 is a detail perspective view, showing the connections for operating the detective-alarm. Fig. 4 is a sectional front elevation of the detective or local alarm mechanism. Fig. 5 is a transverse section of the same.

A is a fire-alarm box, provided with a hinged door, a, which, when opened, gives access to 65 the slide or pull b, by which the circuit-closing drum c is rotated, and also provided with an inner hinged door, d, that gives access to the interior of the box. This mechanism for giving the fire-alarm is of the usual construction, 70 and need not be explained in detail, and it is to be understood that only the outer door, a, has to be opened for sounding an alarm.

The box A is fixed upon the pole B, and the axis e of the circuit-closer c extends through 75 the back plate of the box into the space between such back plate and the pole; and within this space, upon the axis e, I place the devices for operating the local alarm, so that they are not accessible by opening either door of the box. 80

On the pole B, at a suitable height from the ground, so as to be accessible only by use of a ladder, is fixed a box, C. This box contains a gong, f, of large size, and a spring-barrel fitted for operating a trip-wheel, g, that acts 85 upon a pivoted hammer, h, so that the hammer is caused to strike the bell by the rotation of the wheel g.

Upon the gear-wheel i, by which the spring rotates the wheel g, are pins k; and l is a rod 90 extending from the alarm-box C to the lower box, A, which rod, when raised in contact with the pins k, serves to hold the striking mechanism out of action. The rod l extends into the back of the box A, and through an arm, m, 95 that is on the end of the axis e of the circuit-closer. The lower end of the rod l is provided with a button, against which the arm takes so as to draw the rod downward when the axis is rotated; but the connection of the arm m to the rod l should be loose, so that the arm may return to its first position without raising the rod l.

Between the box C and the box A the rod l is 100 contained within a tube, n, so that it cannot be got at or tampered with, and just beneath the box C the rod is provided with a cross-pin, o, which is to be used for raising the rod

by the person who winds the alarm mechanism. It will be observed that none of the parts connected with the local alarm are accessible except for winding up the striking mechanism, 5 and that being placed at an elevation, a ladder must be used to reach it. By this construction and arrangement the door *a* of the fire-alarm box can be opened; but no local alarm will be given until the slide *b* is pulled down 10 to give the fire-alarm, and as soon as the slide *b* is drawn down, the rod *l* being also carried downward, the spring mechanism in the box *C* is released and the alarm will be sounded, and will continue to sound until the spring 15 has run down.

There is no possibility of any interference with this local alarm, and thus, in case a fire-alarm is sounded by any person, attention is immediately drawn to the box.

20 The striking mechanism would necessarily have to be wound after every alarm. This could be readily attended to by the truckmen of the fire-department, who are called out at every alarm, and are always provided with

small ladders that can be conveniently used 25 for the purpose.

The tube through which the rod of the alarm passes may be the usual tube containing the fire-telegraph wires; or a separate tube may be used. The upper end of the rod is bent slightly 30 for extending over the stop-pins, so that the rod may not be caused to fall by the jar of the passing wagons.

Having thus described my invention, I claim as new and desire to secure by Letters Patent— 35

The combination, with a fire-alarm circuit-closer axis, *e*, having arm *m*, of a superposed box containing gong *f*, trip-wheel *g*, pivoted hammer *h*, and gear-wheel *i*, having pins *k*, and the rod *l*, extending into the back of box 40 *A* loosely through arm *m*, having an end button, and provided with a cross-pin, *o*, as and for the purpose specified.

JAMES J. BROPHY.
